UNITED STATES PATENT OFFICE.

AUBREY J. GRINDLE, OF CHICAGO, ILLINOIS, ASSIGNOR TO GRINDLE FUEL EQUIPMENT COMPANY, OF HARVEY, ILLINOIS, A CORPORATION OF ILLINOIS.

AIR AND GAS VALVE MECHANISM FOR MELTING FURNACES.

Application filed January 30, 1922. Serial No. 532,864.

To all whom it may concern:

Be it known that I, AUBREY J. GRINDLE, a citizen of the United States, residing at Chicago, in the county of Cook and State 5 of Illinois, have invented a certain new and useful Improvement in Air and Gas Valve Mechanism for Melting Furnaces, of which the following is a specification.

This invention relates to melting furnaces. 10 It is specially adaptable to devices in which the heat producing material, such as oil, gas, or powdered coal, is delivered to the furnace under pressure from a nozzle or nozzles.

An object is to provide an air circulating 15 system which will keep certain valve mechanisms used in the device cool enough so that they are not injured in the operation of the machine.

The invention consists in a device capable 20 of attaining the foregoing object, which can be comparatively easily and cheaply made, which is satisfactory in use, and is not liable to get out of order. More particularly, the invention consists in many features and de- 25 tails of construction which will be hereafter more fully set forth in the specification and claims.

Referring to the drawings, in which like 30 numerals designate the same parts throughout the several views—

Figure 1 is a plan view, certain parts being shown in section, of the mechanism of this invention in its preferred form;

Figure 2 is a sectional end view at approximately the line 2—2 of Figure 4; and

Figure 3 is an enlarged plan view of the damper control mechanism appearing in Figure 1.

The mechanism of my invention is shown 40 associated with a regenerative furnace of the type wherein two melting chambers 10 and 12 are placed in end to end relation. Each end of the furnace is provided with a large gas flue 30 or 32, having a discharge port 34. The lower end of gas flue 30 terminates in a large horizontally disposed gas passage 36, while flue 32 terminates in another similar sized gas passage 38. These two passages 36 and 38 meet at a convenient point, in the case shown in Figure 1, behind the furnace, and enter a common passage 40, delivering into a conventional stack 42 rising to any suitable height which the conditions of the given furnace may require.

Vertically reciprocatable of gas passage 36, at or immediately adjacent its entrance to passage 40 is a door 52 suspended from a chain or cable 54, passing over suitable pulleys 56 and 58 and having its opposite end attached to a correspondingly reciprocatable door 60 adapted to close passage 38 at or immediately adjacent to the point where it enters flue 40. Owing to the fact that these two doors 52 and 60 are suspended on opposite ends of the cable 54 and the parts are proportioned as shown, one door rises as the other descends, thereby automatically opening one passage, as 38, to flue 40, and closing the passage 36, or vice versa. Any convenient conventional mechanism may be provided for moving the cable 54 to cause this door movement. The particular mechanism shown in the drawing for this purpose includes a shaft 62 driving pulley 58, 75 said shaft carrying a hand wheel 64 manually operable in obvious manner.

As the furnace is intended for use in melting materials requiring a high temperature, the furnace is built in general conventional manner of refractory material, and this is true of the roof 66 of passage 36. The roof 66 is, however, provided immediately adjacent to the door 52 with a vertical port 68 leading to a chamber 70 above the roof 66, 85 which is selectively closable by a door 72 hinged at 74. This door 72 may be opened and closed by any suitable means, the particular one shown in the drawing being a chain 76 adapted to wind about shaft 62 so that when the operator manipulates wheel 64 to raise door 52, door 72 will also be opened. Door 72 closes by the action of gravity whenever the wheel 64 is moved in the opposite direction to lower the door 52. 95

Door 72 has a door section 78^a hinged thereto which door section is provided with a perforation 78 of sufficient size so that the rope 54 may freely pass through it and also so that a suitable quantity of air can pass downward from the outside, first into chamber 70 then through passage 68 into passage 36, even though door 72 may be closed. If for any reason the size of this opening 78 is not sufficient to admit the desired amount of air for the purposes hereafter described, door section 78^a may be folded back upon the door proper 72 as indicated by dotted lines in Figure 5 to provide a larger opening for the admission of air into cham- 1
